INTERNAL COMBUSTION ENGINE

Application filed September 19, 1927, Serial No. 220,295. Renewed October 14, 1931.

This invention relates to internal combustion engines and in part refers more particularly to an improved driving mechanism for the single sleeve valves of an engine having its cylinders arranged radially about a crankshaft. Each cylinder is provided with a single sleeve valve of the "Burt-McCollum" type in which the sleeve is given a combined reciprocating and oscillating movement to control the usual cylinder intake and exhaust ports whereby any point on the sleeve is moved in a closed path with respect to the cylinder ordinarily surrounding the sleeve. My invention, in part, has to do with the aforesaid type of sleeve valve movement where the engine cylinders are arranged radially about the crankshaft.

Radial engines, in general, are particularly adapted for aircraft propulsion and my invention is especially useful in this field although not necessarily limited thereto as my engine may be used wherever desired.

One feature of my invention provides a simply constructed sleeve driving mechanism by reason of which much of the usual gear train is eliminated. Furthermore a relatively light weight engine is provided and the simplicity of the mechanism will permit of a relatively low manufacturing cost. Manufacturers of aircraft engines are constantly striving to reduce the number of valve operating parts in order to simplify the engine so as to reduce the cost of manufacture, reduce the weight of the engine as much as possible, and reduce the hazard of engine failure since each part of the operating mechanism introduces an element of possible breakage and engine failure. My invention is a decided step in advance in meeting these desired qualities in an engine.

With the foregoing objects in view I have provided an operating element connected to drive each of the sleeve valves for the cylinders of a radial engine, the operating element being driven in a simple manner from the engine crankshaft.

In one embodiment of my invention the driving mechanism for the sleeve valves is arranged to drive the power take-off portion

of the engine crankshaft at reduced engine speed.

A further feature of my invention resides in an increased air cooling efficiency for an air cooled engine, particularly for a radial internal combustion engine, the manifolding being so constructed and arranged so as to eliminate "dead air pockets" in the vicinity of the manifolding.

A still further feature resides in an improved structure for cooling the recessed cylinder heads and spark plugs ordinarily located therein.

With the above and other objects in view my invention resides in the novel combination and arrangement of parts more particularly hereinafter described.

Referring to the drawings in which like reference characters represent corresponding parts,

Fig. 1 is a section view through the engine illustrating the sleeve driving mechanism,

Fig. 2 is a front elevation view of the engine partly in section along 2-2 of Fig. 1 to illustrate the sleeve driving mechanism,

Fig. 3 is a detail section along 3-3 of Fig. 2 illustrating the manifolding construction for a typical cylinder, and

Fig. 4 is a view corresponding to Fig. 1 illustrating a modification of my invention.

In the drawings the engine may comprise a main crank case 10 and end cover 11 together housing the crankshaft 12 journalled in bearings 13, 14, and 15.

A plurality of cylinders 16 are arranged with their axes radiating from the crankshaft preferably in a common plane. Each cylinder 16 has its outer end closed by a cylinder head 17 which may extend within the cylinder to provide an annular sleeve pocket 18 and a recess 19 for one or more spark plugs 20. The single sleeve valve 21 is preferably located between the cylinder 16 and piston A, the cylinders being provided with intake and exhaust ports 22, and 23 respectively controlled by the sleeve valve intake and exhaust ports 24, and 25 in a manner well known in the "Burt-McCollum" type of engine. The several pistons A are suitably connected by

rods B to drive the crank C of the shaft 12. Ordinarily in a radial engine there is provided a master rod B' connected with one of the pistons, the remaining connecting rods B being articulated on the master rod by a pivotal connection D.

In order to impart to the sleeve valves 21 the desired combined reciprocating and oscillating movement to control the cyclic functioning of the engine, each sleeve is formed with a ball and socket 26 slidably receiving a crank 27 rotatable in a bearing 28 conveniently located in a crank case wall 29 between the valve driving mechanism and the crank 24. The crank 27 is driven by a second crank 30 extending in direction opposite to the crank 27. The cranks 27 and 30 together form a unitary driving element or mechanism rotatable in bearing 28.

The several cranks 30 are journalled in an element 31 which is in the nature of a strap mounted on an eccentric 32. This eccentric is rotatable in a bearing 33 conveniently carried by the cover 11 and may be driven in a suitable manner from the crankshaft 12. In the embodiment illustrated in Figs. 1 and 2, the eccentric 32 is provided with an internal gear 33' meshing with a pinion 34 keyed at 35 to the crankshaft 12.

The pinion 34 drives the eccentric 32 which rotates in the bearing 33 off-center with respect to the crankshaft 12 and at half the crankshaft speed whereby the sleeve valves will perform their cycle at half engine speed where a four stroke cycle engine is desired.

The eccentric 32 operates the strap or element 31 whereby all points on the latter move in the same direction at any time, any point moving in a circle whereby the cranks 30 are rotated in unison. By relatively angularly locating the cranks 27 and 30 for each sleeve the desired relative timing of the various cylinders is obtained. In Fig. 2 I have illustrated the relative positions of the cranks 27

and 30 for a five cylinder engine although it is obvious that any desired number of cylinders may be provided. The mechanism will operate without providing a bearing for the eccentric 32, as the bearing 33, but such a bearing is desirable to relieve the thrust of the driving pinion 34. Where the engine is used for aircraft the propeller may be conveniently mounted, if desired, on the end 12^a of the crankshaft 12.

With reference to Fig. 4 I have illustrated a modification wherein the eccentric 32' is carried by the power take-off shaft 12^b separate from the main portion of the crankshaft 12. The shaft 12^b is rotatably mounted in bearings 15^a and 15^b conveniently formed in the cover 11^a, the axis of the shaft 12^b being located on the axis of the gear 33' which is also the axis of rotation of the eccentric 32'. I have thus provided a power take-off shaft driven at reduced engine speed, such as half

speed in the illustrated embodiment. Furthermore the bearing for the shaft 12^b also provides the bearing for the eccentric 32'. Where the engine is used for aircraft propulsion the airscrew or propeller may be mounted on the shaft 12^b it being desirable in many instances to drive the propeller at reduced engine speed. My invention thus provides a reduced drive without requiring the addition of auxiliary reduction gearing such as commonly employed, the valve driving mechanism including an element in common with the power take-off.

In order to cool the recessed cylinder head 17 and spark plug 20 located therein I have provided a deflecting element 36 which has a portion bridging the cylinder head and projecting therebeyond across the path of the slip-stream or air current indicated by the arrows in Fig. 1. This deflecting element 36 may be secured to the cylinder head by fasteners 37, the deflecting element preferably also having a baffle portion 38 extending inwardly in the recess 19 but terminating a distance away from the bottom of the recess so as to cause the deflected air to circulate around the bottom of the recess 19 and around the spark plug 20, maintaining these parts in a properly cool condition. By locating the deflecting element 36 intermediate the front and rear of the cylinder head with respect to the travel of the slipstream or cooling air current an efficient flow of cooling air is obtained, the deflected air passing upwardly on the right of baffle 38 as viewed in Fig. 1 and joining the slipstream passing above the cylinder, the slipstream at this point assisting in the circulation of the cooling air. If desired the baffle portion 38 may be omitted.

Ordinarily the intake manifold is located at the rear of the engine and the exhaust manifold at the front, although the position of these parts might be reversed. I have shown the intake manifold 39 located in the customary position for radial engines. The exhaust gases are removed at a plurality of points, each cylinder being provided with diverging conduits 40, best shown in Fig. 3, fitted with exhaust manifolds or manifold sections 41. Each manifold 41 may be connected with adjacent conduits 40 of adjacent cylinders as shown in Fig. 2. Heretofore difficulty has been experienced in properly cooling the cylinders in the vicinity of the exhaust manifold which tends to be the hottest part of the engine and where branched exhaust manifolds were used "dead air pockets" formed between the branches where they were connected to the cylinders. By offsetting the exhaust manifolds to either side of the axis of the cylinders as viewed in the direction of the slipstream, and by diverging the exhaust conduits 40, the portion of the cylinder in the vicinity of the exhaust con-

duits is exposed to an adequate supply of cooling air and the formation of "dead air pockets" is avoided. Thus the air striking the cylinder between conduits 40 may escape to either side as indicated by the arrows in Fig. 3, the diverging walls of the conduits 40 permitting such escape. The exhaust manifolds 41 may exhaust individually into the atmosphere or may be joined together for a single discharge as desired.

What I claim as my invention is:

1. An internal combustion engine comprising in combination, a crankshaft, a plurality of ported cylinders having their axes disposed radially about the crankshaft, pistons within said cylinders respectively connected with the crankshaft, a single sleeve valve for each cylinder provided with ports cooperating with the cylinder ports, said sleeve valves having their axes in common with the respective cylinder axes and each having a combined reciprocating and oscillating movement with respect to its axis, crank means connected with each sleeve valve, an element connected with the crank means of each sleeve valve, and means for driving said element from the crankshaft for imparting the aforesaid movement to the sleeve valves.
2. An internal combustion engine comprising in combination, a crankshaft, a plurality of ported cylinders having their axes disposed radially about the crankshaft, pistons within said cylinders respectively connected with the crankshaft, a single sleeve valve for each cylinder provided with ports cooperating with the cylinder ports, said sleeve valves having their axes in common with the respective cylinder axes and each having a combined reciprocating and oscillating movement with respect to its axis, a crank connected with each sleeve valve, a second crank operably connected with each of the first said cranks, a strap connecting each of the said second cranks, an eccentric driving the strap and formed with an internal gear surrounding the crankshaft, and a driving pinion carried by the crankshaft meshing with the said internal gear whereby the sleeve valves are given the aforesaid movement.
3. An internal combustion engine comprising in combination, a crankshaft, a plurality of ported cylinders having their axes disposed radially about the crankshaft, pistons within said cylinders respectively connected with the crankshaft, a single sleeve valve for each cylinder provided with ports cooperating with the cylinder ports, said sleeve valves having their axes in common with the respective cylinder axes, and each having a combined reciprocating and oscillating movement with respect to its axis, and means for driving the sleeve valves with the aforesaid movement including an eccentric driven from the crankshaft and a strap driven by the eccentric.
4. An internal combustion engine comprising

ing in combination, a crankshaft, a plurality of ported cylinders having their axes disposed radially about the crankshaft, pistons within said cylinders respectively connected with the crankshaft, a single sleeve valve for each cylinder provided with ports cooperating with the cylinder ports, said sleeve valves having their axes in common with the respective cylinder axes and each having a combined reciprocating and oscillating movement with respect to its axis, crank means connected with each sleeve valve, a driving pinion carried by the crankshaft, an element connected with each of the said crank means, and an eccentric transmitting the drive from the pinion to the said element whereby the aforesaid movement is imparted to the sleeve valves.

5. An internal combustion engine comprising in combination, a crankshaft, a plurality of ported cylinders having their axes disposed radially about the crankshaft, pistons within said cylinders respectively connected with the crankshaft, a single sleeve valve for each cylinder provided with the ports cooperating with the cylinder ports, said sleeve valves having their axes in common with the respective cylinder axes and each having a combined reciprocating and oscillating movement with respect to its axis, a crank connected with each sleeve valve, a second crank operably connected with each of the first said cranks, a strap connecting each of the said second cranks, an eccentric driving the strap and formed with an internal gear surrounding the crankshaft, and a driving pinion carried by the crankshaft meshing with the said internal gear whereby the sleeve valves are given the aforesaid movement.

6. A sleeve valve driving mechanism comprising in combination with a crankshaft and a plurality of engine cylinders disposed radially about said crankshaft each cylinder having a sleeve valve associated therewith, and means including an eccentric and strap intermediate the crankshaft and sleeve valves for imparting to the sleeve valves a combined reciprocating and oscillating movement.

7. An internal combustion engine comprising in combination, a crankshaft, a plurality of ported cylinders having their axes disposed radially about the crankshaft, pistons within said cylinders respectively connected with the crankshaft, a single sleeve valve for each cylinder provided with ports cooperating with the cylinder ports, said sleeve valves having their axes in common with the respective cylinder axes and each having a combined reciprocating and oscillating movement with respect to its axis, a crank case, a crank case cover, crank means rotatably supported by the crank case and connected with each sleeve valve, a strap connected with the crank means of each sleeve valve, an eccentric having a bearing on the crank case cover for

operating the strap, and means for driving the eccentric from the crankshaft to impart to the sleeve valves the aforesaid movement.

8. An internal combustion engine comprising in combination, a crankshaft, a plurality of ported cylinders having their axes disposed radially about the crankshaft, pistons within said cylinders respectively connected with the crankshaft, a single sleeve valve for

10 each cylinder provided with ports cooperating with the cylinder ports, said sleeve valves having their axes in common with the respective cylinder axes and each having a combined reciprocating and oscillating movement with respect to its axis, crank means connected with each sleeve valve, an element connected with the crank means of each sleeve valve, and a shaft driven from the crankshaft and driving said element whereby the sleeve valves are given the aforesaid movement.

9. An internal combustion engine comprising in combination, a crankshaft, a plurality of ported cylinders having their axes disposed radially about the crankshaft, pistons within said cylinders respectively connected with the crankshaft, a single sleeve valve for each cylinder provided with ports cooperating with the cylinder ports, said sleeve valves having their axes in common with the respective cylinder axes, and each having a combined reciprocating and oscillating movement with respect to its axis, and driving means between the crankshaft and sleeve valves including a rotatable shaft having its axis offset from the crankshaft axis.

10. An internal combustion engine comprising in combination, a crankshaft, a plurality of ported cylinders having their axes disposed radially about the crankshaft, pistons within said cylinders respectively connected with the crankshaft, a single sleeve valve for each cylinder provided with ports cooperating with the cylinder ports, said sleeve valves having their axes in common with the respective cylinder axes and each having a combined reciprocating and oscillating movement with respect to its axis, a driving pinion mounted on the crankshaft, a power take-off shaft rotatably driven from said pinion about an axis offset from the crankshaft axis, said power take-off shaft provided with an eccentric, a strap operated by the eccentric, and means connecting the strap and sleeve valves whereby the sleeve valves are given the aforesaid movement.

11. An internal combustion engine comprising in combination, a crankshaft, a plurality of ported cylinders having their axes disposed radially about the crankshaft, pistons within said cylinders respectively connected with the crankshaft, a single sleeve valve for each cylinder provided with ports cooperating with the cylinder ports, said sleeve valves having their axes in common with the respective cylinder axes and each

having a combined reciprocating and oscillating movement with respect to its axis, a driving pinion mounted on the crankshaft, a power take-off shaft having an internal gear meshing with said pinion and provided with an eccentric, and means operated by the eccentric connecting the sleeve valves for imparting the aforesaid movement to the sleeve valves.

12. An internal combustion engine having a plurality of cylinders radially arranged about the engine crankshaft, a crankshaft housing structure, valving means for the cylinders, and a reduction mechanism transmitting a drive between the crankshaft and valving means including a power take-off shaft rotatable about an axis offset from the crankshaft axis said power take-off shaft extending outwardly through and beyond said housing.

13. A sleeve valve driving mechanism comprising in combination with a crankshaft and a plurality of engine cylinders disposed radially about said crankshaft; each cylinder having sleeve valve means associated therewith, and means including an eccentric and strap intermediate the crankshaft and sleeve valve means for moving all sleeve valve means of said cylinders.

14. An internal combustion engine comprising in combination, a crankshaft, a plurality of ported cylinders having their axes disposed radially about the crankshaft, pistons within said cylinders respectively connected with the crankshaft, a single sleeve valve for each cylinder provided with ports cooperating with the cylinder ports, said sleeve valves having their axes in common with the respective cylinder axes and each having a combined reciprocating and oscillating movement with respect to its axis, driving means connected with each sleeve valve, an operating member extending around the crankshaft for connection with the driving means of each sleeve valve whereby the operating member is fixed against rotation around the crankshaft, and means for moving said operating member from the crankshaft in an orbital path for imparting the aforesaid movement to the sleeve valves.

15. An internal combustion engine embodying the combination recited in claim 14 in which the operating member comprises a strap and in which the crankshaft moving means for the strap includes an eccentric.

16. An internal combustion engine embodying the combination recited in claim 14 in which the operating member is moved at reduced crankshaft speed.

17. An internal combustion engine embodying the combination recited in claim 14 in which the crankshaft moving means includes a power take-off shaft rotatable about an axis offset from the crankshaft axis.

18. An internal combustion engine having

- a crankcase and comprising in combination, a crankshaft, a plurality of ported cylinders having their axes disposed radially about the crankshaft, pistons within said cylinders respectively connected with the crankshaft, a sleeve valve means for each cylinder provided with ports cooperating with the cylinder ports, a wall adjacent one end of the crankcase and offset to one side of the plane of the engine containing the cylinder axes, and a common sleeve valve operating means eccentrically mounted with respect to the crankshaft to that side of the wall remote from the cylinder axes and operatively connected with said crankshaft. 15
19. An internal combustion engine having a crankcase and comprising in combination, a crankshaft, a plurality of ported cylinders having their axes disposed radially about the crankshaft, pistons within said cylinders respectively connected with the crankshaft, a sleeve valve means for each cylinder provided with ports cooperating with the cylinder ports, a wall adjacent one end of the crankcase and offset to one side of the plane of the engine containing the cylinder axes, a plurality of sleeve valve actuating means supported by said wall, and a common operating element eccentrically mounted with respect to the crankshaft arranged to be connected with all of said sleeve valve actuating means and operatively connected with said crankshaft. 25
20. An internal combustion engine having a crankcase and comprising in combination, a crankshaft, a plurality of ported cylinders having their axes disposed radially about the crankshaft, pistons within said cylinders respectively connected with the crankshaft, a sleeve valve means for each cylinder provided with ports cooperating with the cylinder ports, a wall adjacent one end of the crankcase and offset to one side of the plane of the engine containing the cylinder axes, a plurality of sleeve valve actuating cranks rotatably supported by said wall and having axes parallel with the crankshaft axis, and a common operating element eccentrically mounted with respect to the crankshaft arranged to be connected with all of said sleeve valve actuating cranks and operatively connected with said crankshaft. 45
21. An internal combustion engine having a crankshaft and a plurality of cylinders radially arranged about the engine crankshaft, a crankshaft housing structure, valving means for the cylinders, a reduction mechanism transmitting a drive between the crankshaft and valving means and including an intermediate driving intermediary, and a power take-off shaft secured to said driving intermediary, said power take-off shaft extending outwardly through and beyond said housing. 65
22. An internal combustion engine having a crankshaft and a plurality of cylinders radially arranged about the engine crankshaft, a crankshaft housing structure, valving means for the cylinders, a reduction mechanism transmitting a drive between the crankshaft and valving means and including an intermediate driving intermediary, and a power take-off shaft secured to said driving intermediary and rotatable about an axis offset from the crankshaft axis, said power take-off shaft extending outwardly through and beyond said housing. 70
23. An internal combustion engine having a crankshaft and a plurality of cylinders radially arranged about the engine crankshaft, a crankshaft housing structure, valving means for the cylinders, a reduction mechanism transmitting a drive between the crankshaft and valving means and including an intermediate internal gear operatively connected with said crankshaft, and a power take-off shaft secured to said gear, said power take-off shaft extending outwardly through and beyond said housing. 75
24. In a sleeve valve engine, the combination with a crankshaft and a plurality of ported cylinders disposed radially about the crankshaft, each cylinder having a piston operatively connected to the crankshaft, sleeve valve means ported for intake and exhaust and associated with each cylinder, and means for operating said sleeve valve means including a gear driven by said crankshaft, an eccentric driven by said gear, and a sleeve operating element actuated by said eccentric and connected with each sleeve valve means for directing movement of the same whereby the sleeve ports and the ports of the associated cylinder will cooperate to control the admission of fuel to the cylinders and the exhaust of gas from the cylinders. 90
25. In a sleeve valve engine, the combination with a crankshaft and a plurality of ported cylinders disposed radially about the crankshaft, each cylinder having a piston operatively connected to the crankshaft, sleeve valve means ported for intake and exhaust and associated with each cylinder, and means for operating said sleeve valve means including a gear driven by said crankshaft, an eccentric driven by said gear at one half crankshaft speed, and a sleeve operating element actuated by said eccentric and connected with each sleeve valve means for directing movement of the same whereby the sleeve ports and the ports of the associated cylinder will cooperate to control the admission of fuel to the cylinders and the exhaust of gas from the cylinders. 105
26. In a sleeve valve engine, the combination with a crankshaft and a plurality of ported cylinders disposed radially about the crankshaft, each cylinder having a piston operatively connected to the crankshaft, sleeve valve means ported for intake and exhaust 110
- 115
- 125
- 130

and associated with each cylinder, crank means associated with each of said sleeve valve means, and means for operating said sleeve valve means including a gear driven by said crankshaft, an eccentric driven by said gear, and an element actuated by said eccentric and connected with each of said crank means for actuating said sleeve valve means whereby the sleeve ports and the ports of the associated cylinder will cooperate to control the admission of fuel to the cylinders and the exhaust of gas from the cylinders.

27. In a sleeve valve engine, the combination with a crankshaft and a plurality of 10 ported cylinders disposed radially about the crankshaft, each cylinder having a piston operatively connected to the crankshaft, sleeve valve means ported for intake and exhaust and associated with each cylinder, crank 15 means associated with each of said sleeve valve means and supported for rotation about an axis parallel to the axis of the engine crankshaft, and means for operating said sleeve valve means including a gear driven by 20 said crankshaft, an eccentric driven by said gear, and an element actuated by said eccentric and connected with each of said crank means for actuating said sleeve valve means whereby the sleeve ports and the ports of the 25 associated cylinder will cooperate to control the admission of fuel to the cylinders and the exhaust of gas from the cylinders.

28. In a sleeve valve engine, the combination with a crankshaft and a plurality of 30 ported cylinders disposed radially about the crankshaft, each cylinder having a piston operatively connected to the crankshaft, sleeve valve means ported for intake and exhaust and associated with each cylinder, crank 35 means associated with each of said sleeve valve means and supported for rotation about an axis parallel to the axis of the engine crankshaft, and means for operating said sleeve valve means including a gear driven by 40 said crankshaft, an eccentric driven by said gear, and an element actuated by said eccentric and connected with each of said crank means for actuating said sleeve valve means whereby the sleeve ports and the ports of the 45 associated cylinder will cooperate to control the admission of fuel to the cylinders and the exhaust of gas from the cylinders, said element supported for movement in a 50 plane parallel to the engine plane containing 55 the cylinder axes.

29. In a sleeve valve engine, the combination with a crankshaft and a plurality of 60 ported cylinders disposed radially about the crankshaft, each cylinder having a piston operatively connected to the crankshaft, sleeve valve means ported for intake and exhaust and associated with each cylinder, crank 65 means associated with each of said sleeve valve means and supported for rotation about an axis parallel to the axis of the engine

crankshaft, and means for operating said sleeve valve means including a gear driven by said crankshaft, an eccentric driven by said gear, and an element actuated by said eccentric and connected with each of said crank means for actuating said sleeve valve means whereby the sleeve ports and the ports of the associated cylinder will cooperate to control the admission of fuel to the cylinders and the exhaust of gas from the cylinders, said element having an orbital movement in a plane parallel to the engine plane containing the cylinder and sleeve axes.

30. An internal combustion engine comprising a crankshaft, a plurality of cylinders radially disposed about the crankshaft, a piston operable in each cylinder, means connecting the pistons and crankshaft, sleeve valve means associated with each cylinder, and sleeve valve operating means including an eccentrically driven sleeve valve actuating element and reduction gearing intermediate said element and crankshaft.

31. An internal combustion engine comprising a crankshaft, a plurality of cylinders radially disposed about the crankshaft, a piston operable in each cylinder, means connecting the pistons and crankshaft, sleeve valve means associated with each cylinder, and sleeve valve operating means including an eccentrically driven sleeve valve actuating element and reduction gearing intermediate said element and crankshaft, said gearing including a driving gear secured to said crankshaft and a driven gear supported for rotation about an axis offset in parallel relation with respect to the crankshaft axis.

32. An internal combustion engine comprising a crankshaft, a plurality of cylinders radially disposed about the crankshaft, a piston operable in each cylinder, means connecting the pistons and crankshaft, sleeve valve means associated with each cylinder, and sleeve valve operating means including a sleeve valve actuating element, an eccentric for operating same, and reduction gearing intermediate the eccentric and crankshaft, said gearing including driving gear secured to said crankshaft, and a driven gear supported for rotation about an axis offset in parallel relation with respect to the crankshaft axis, said driven gear operatively connected with said eccentric.

33. An internal combustion engine comprising a crankshaft, a plurality of cylinders radially disposed about the crankshaft, a piston operable in each cylinder, means connecting the pistons and crankshaft, sleeve valve means associated with each cylinder, and sleeve valve operating means including a sleeve valve actuating element, an eccentric for operating same, and reduction gearing intermediate the eccentric and crankshaft, said gearing including a driving gear

secured to said crankshaft, and a driven gear operatively connected with said eccentric.

34. An internal combustion engine of the sleeve valve type having a crankcase and comprising in combination, a crankshaft, a plurality of cylinders and associated sleeve valve means positioned radially about the crankshaft, said cylinders and associated sleeve valve means respectively having cooperating intake and exhaust ports, a wall portion associated with said crankcase and extending substantially perpendicularly to the axis of the crankshaft to one side of the engine plane containing the cylinder axes, and means for operating said sleeve valve means including an eccentrically driven element located to that side of the wall remote from the engine plane containing the cylinder axes, and connecting said element with the said sleeve valve means.

35. An internal combustion engine of the sleeve valve type having a crankcase and comprising in combination, a crankshaft, a plurality of cylinders and associated sleeve valve means positioned radially about the crankshaft, said cylinders and associated sleeve valve means respectively having cooperating intake and exhaust ports, a wall portion associated with said crankcase and extending substantially perpendicularly to the axis of the crankshaft to one side of the engine plane containing the cylinder axes, a common sleeve valve operating element, reduction gearing intermediate said element and crankshaft, and means extending through said wall for connecting said element with said sleeve valve means.

36. An internal combustion engine of the sleeve valve type having a crankcase and comprising in combination, a crankshaft, a plurality of cylinders and associated sleeve valve means positioned radially about the crankshaft, said cylinders and associated sleeve valve means respectively having cooperating intake and exhaust ports, a wall portion associated with said crankcase and extending substantially perpendicularly to the axis of the crankshaft to one side of the engine plane containing the cylinder axes, a sleeve valve operating element, reduction gearing intermediate said element and crankshaft, and means extending through said wall for connecting said element with said sleeve valve means, said reduction gearing including a driving gear secured to the crankshaft and a driven gear supported for rotation about an axis offset in parallel relation with respect to the crankshaft axis.

37. An internal combustion engine of the sleeve valve type having a crankcase and comprising in combination, a crankshaft, a plurality of cylinders and associated sleeve valve means positioned radially about the crankshaft, said cylinders and associated sleeve

valve means respectively having cooperating intake and exhaust ports, a wall portion associated with said crankcase and extending substantially perpendicularly to the axis of the crankshaft to one side of the engine plane containing the cylinder axes, and sleeve valve operating means including an element located to that side of the wall remote from the engine plane containing the cylinder axes, an eccentric for operating said element, reduction gearing intermediate said eccentric and crankshaft and including a driving gear secured to the crankshaft and a driven gear operatively connected with the eccentric, and means extending through said wall for connecting said element with said sleeve valve means.

38. An internal combustion engine of the sleeve valve type having a crankcase and comprising in combination, a crankshaft, a plurality of cylinders and associated sleeve valve means positioned radially about the crankshaft, said cylinders and associated sleeve valve means respectively having cooperating intake and exhaust ports, a wall portion associated with said crankcase and extending substantially perpendicularly to the axis of the crankshaft to one side of the engine plane containing the cylinder axes, and sleeve valve operating means including an element located to that side of the wall remote from the engine plane containing the cylinder axes, an eccentric for operating said element, reduction gearing intermediate said eccentric and crankshaft and including a driving gear secured to the crankshaft and a driven gear operatively connected with the eccentric, and means extending through said wall for connecting said element with said sleeve valve means.

39. An internal combustion engine of the sleeve valve type having a crankcase and comprising in combination, a crankshaft, a plurality of cylinders and associated sleeve valve means positioned radially about the crankshaft, said cylinders and associated sleeve valve means respectively having cooperating intake and exhaust ports, a wall portion associated with said crankcase and extending substantially perpendicularly to the axis of the crankshaft to one side of the engine plane containing the cylinder axes, and sleeve valve operating means including an element located to that side of the wall remote from the engine plane containing the cylinder axes, an eccentric for operating said element, reduction gearing intermediate said eccentric and crankshaft and including a driving gear secured to the crankshaft and a driven gear operatively connected with the eccentric, and means extending through said wall for connecting said element with said sleeve valve means, said crank means supported by said wall for rotation about axes

extending substantially parallel with the crankshaft axis.

40. A sleeve valve engine having a crankcase and comprising a crankshaft, a wall portion associated with said crankcase and extending substantially perpendicular to the axis of the crankshaft, a plurality of cylinders and associated sleeve valve means positioned radially about the crankshaft on one side of said wall portion, and sleeve valve operating means including an eccentrically driven element located to that side of the wall portion remote from the engine plane containing the cylinder axes, and means extending through said wall portion for driving the sleeves from said element, said means including a plurality of sleeve driving units each including a bearing member, said wall portion having a series of openings spaced around the crankshaft for receiving said bearing members.

41. A sleeve valve engine having a crankcase and comprising a crankshaft, a wall portion associated with said crankcase and extending substantially perpendicular to the axis of the crankshaft, a plurality of cylinders and associated sleeve valve means positioned radially about the crankshaft on one side of said wall portion, and sleeve valve operating means including an element located to that side of the wall portion remote from the engine plane containing the cylinder axes, an eccentric for driving said element, means operatively connecting said eccentric in driving relation with said crankshaft, and means extending through said wall portion for driving the sleeves from said element, said means including a plurality of sleeve driving units each including a crank and a bearing member, said wall portion having a series of openings spaced around the crankshaft for receiving said bearing members.

42. In an internal combustion engine of the sleeve valve type having a crankcase, a crankshaft supported in part by said crankcase, a wall portion associated with said crankcase, a plurality of cylinders and associated sleeve valve means positioned radially about the crankshaft on one side of said wall portion, sleeve valve operating means driven from said crankshaft and including an eccentric and an operating element driven by the eccentric, said element and eccentric located to that side of the wall portion remote from the engine plane containing the cylinder axes, and sleeve actuating cranks operatively connected with said element and extending through said wall portion, said wall provided with bearing means for supporting said crankshaft and said sleeve actuating cranks.

43. In an internal combustion engine of the sleeve valve type having a crankcase, a crankshaft supported in part by said crankcase, a wall portion associated with said crankcase, a plurality of cylinders and associated sleeve valve means positioned radially

about the crankshaft on one side of said wall portion, sleeve valve operating means driven from said crankshaft and including an eccentric and an operating element driven by the eccentric, said element and eccentric located to that side of the wall portion remote from the engine plane containing the cylinder axes, and sleeve actuating cranks operatively connected with said element and extending through said wall portion, said wall provided with bearing means for supporting said crankshaft and said sleeve actuating cranks, and a casing secured to said crankcase for housing said sleeve operating means, said casing provided with a bearing structure for supporting said crankshaft.

44. In an internal combustion engine of the sleeve valve type having a crankcase, a crankshaft supported in part by said crankcase, a wall portion associated with said crankcase, a plurality of cylinders and associated sleeve valve means positioned radially about the crankshaft on one side of said wall portion, sleeve valve operating means driven from said crankshaft and including an eccentric and an operating element driven by the eccentric, said element and eccentric located to that side of the wall portion remote from the engine plane containing the cylinder axes, and sleeve actuating cranks operatively connected with said element and extending through said wall portion, said wall provided with bearing means for supporting said crankshaft and said sleeve actuating cranks, and a casing secured to said crankcase for housing said sleeve operating means, said casing provided with a bearing structure for supporting said crankshaft.

45. In an internal combustion engine of the sleeve valve type having a crankcase, a crankshaft supported in part by said crankcase, a wall portion associated with said crankcase, a plurality of cylinders and associated sleeve valve means positioned radially about the crankshaft on one side of said wall portion, sleeve valve operating means driven from said crankshaft and including an eccentric and an operating element driven by the eccentric, said element and eccentric located to that side of the wall portion remote from the engine plane containing the cylinder axes, and sleeve actuating cranks operatively connected with said element and extending through said wall portion, said wall provided with bearing means for supporting said crankshaft and said sleeve actuating cranks, and a casing secured to said crankcase for housing said sleeve operating means, said casing provided with eccentrically arranged bearing structures for respectively supporting said crankshaft and said eccentric.

46. In an internal combustion engine of the radial sleeve valve type including a crankcase, a cylinder, a crankshaft, and sleeve valve means for each cylinder, the combination

- therewith of a sleeve valve actuating crank rotatably supported within said crankcase and having an axis extending substantially parallel with the crankshaft axis, and means within said crankcase and including an eccentric for connecting said sleeve valve crank with said crankshaft. 5 a plurality of cylinders and associated sleeve valve means disposed radially about the crankshaft, and sleeve valve operating means including an eccentric, gearing intermediate said eccentric and crankshaft including an internal gear carried by said eccentric, and sleeve valve actuating devices connecting said eccentric to said sleeve valve means. 70
47. In an internal combustion engine of the fixed radial cylinder type having in combination with sleeve valve means one for each cylinder, cranked operating shafts one for each sleeve and rotatably mounted adjacent to the several cylinders for actuating said sleeve valve means, means for driving said cranked shafts and including a common driving element and an eccentric operatively connected with said crankshaft for driving said element, said cranked operating shafts being parallel with the engine crankshaft. 10 54. An internal combustion engine having a plurality of cylinders radially arranged about the engine crankshaft, a housing structure, and a reduction drive mechanism associated therewith and including an internal gear, said housing structure provided with eccentric bearings. 75
48. In a sleeve valve engine of the radial cylinder type and including a crankcase having a wall associated therewith and extending generally in a plane substantially parallel with the engine plane containing the cylinder axes, a crankshaft supported by said crankcase and extending through said wall, sleeve valve means associated with each cylinder, sleeve valve actuating means, a common operating element connected with said sleeve valve actuating means, and means including an eccentric for driving said element from said crankshaft. 20 55. An internal combustion engine having a plurality of cylinders radially arranged about the engine crankshaft, a housing structure, and a reduction drive mechanism associated therewith including a driving gear carried by the crankshaft and an internal gear engaging said driving gear, said housing provided with eccentric bearings one for said crankshaft and the other for said internal gear. 80
49. A sleeve valve driving mechanism for a sleeve valve engine having a crankshaft and a plurality of cylinders and associated sleeve valve means disposed radially about the crankshaft, said sleeve valve driving mechanism including sleeve valve actuating elements and means including an eccentric driven by said crankshaft and operatively connected with said actuating elements. 25 56. In an engine having a crankshaft and a plurality of engine cylinders disposed radially about the crankshaft, sleeve valve means associated with each cylinder, and sleeve driving means including a plurality of crank elements each connected with one of said sleeve valve means, and means operatively connecting said eccentrics with said crankshaft including a common driving element and eccentric means driven by said crankshaft for actuating said common driving element. 90
50. In a sleeve valve engine having a cylinder, a crankshaft, sleeve valve means associated with the engine cylinder, a sleeve valve actuating device, and means including an eccentric directly driven by said crankshaft for operating said sleeve valve actuating device. 30 57. In an engine having a crankshaft and a plurality of engine cylinders disposed radially about the crankshaft, sleeve valve means associated with each cylinder, and sleeve driving means including a plurality of crank elements each connected with one of said sleeve valve means, and means operatively connecting said eccentrics with said crankshaft including a common driving element and eccentric means driven by said crankshaft for actuating said common driving element. 100
51. In a sleeve valve engine having a cylinder, a crankshaft, sleeve valve means associated with the engine cylinder, and sleeve valve operating means including an eccentric, gearing intermediate said eccentric and crankshaft, and a sleeve valve actuating device connecting said eccentric to the sleeve valve means. 35 110
52. In a sleeve valve engine, a crankshaft, a plurality of cylinders and associated sleeve valve means disposed radially about the crankshaft, and sleeve valve operating means including an eccentric, gearing intermediate said eccentric and crankshaft, and sleeve valve actuating devices connecting said eccentric to said sleeve valve means. 40
53. In a sleeve valve engine, a crankshaft, 120
- In witness whereof, I hereunto subscribe my name this 12th day of September, A. D. 1927. 125
- ARCHIE MACPHAIL NIVEN. 130
